UNITED STATES PATENT OFFICE.

WILLIAM E. HATHAWAY, EDGAR F. HATHAWAY, AND ALONZO B. WOODARD,
OF HORNELLSVILLE, NEW YORK.

DESIGN FOR A FENCING-STRAND.

SPECIFICATION forming part of Design No. 19,436, dated November 19, 1889.

Application filed October 24, 1889. Serial No. 328,076. Term of patent 14 years.

To all whom it may concern:

Be it known that we, WILLIAM E. HATHAWAY, EDGAR F. HATHAWAY, and ALONZO B. WOODARD, citizens of the United States, residing at Hornellsville, in the county of Steuben and State of New York, have invented and produced a new and original Design for Fencing-Strands, of which the following is a specification.

10 The object of our design is to provide a novel and ornamental fencing-strand; and the leading feature thereof consists in the pattern herein shown for a fence-strand.

15 The design is illustrated by the accompanying drawing, in which the figure is a plan view of so much of the strand as is necessary to exhibit the pattern.

In the drawing, the numerals 1 and 2 indi-

cate two longitudinal substantially-parallel lines, each broken at intervals by lines 3, 20 which extend at an angle to the longitudinal lines. A zigzagged line 4 extends between the longitudinal lines, and from the latter are projected loops 5, alternating with each other.

What we claim is—

25 The design for a fencing-strand, substantially as shown and described.

In testimony whereof we have affixed our signatures in presence of two witnesses.

WILLIAM E. HATHAWAY.
EDGAR F. HATHAWAY.
ALONZO B. WOODARD.

Witnesses:

CHARLES F. KEYSER,
S. H. CRANE.
